DESIGN FOR A LACE FABRIC OR THE LIKE

Walter F. Breuss, Leonia, N. J.

Application June 10, 1938, Serial No. 77,728

Term of patent 3½ years

To all whom it may concern:

Be it known that I, Walter F. Breuss, a citizen of the United States, residing in Leonia, county of Bergen, and State of New Jersey, have invented a new, original, and ornamental Design for a Lace Fabric or the like, of which the following is a specification, reference being had to the accompanying drawing, forming part thereof.

The drawing is a plan view of a lace fabric or the like showing my new design.

The design which is an open lace fabric is shown on a black surface to bring out the details thereof.

I claim:

The ornamental design for a lace fabric or the like as shown and described.

WALTER F. BREUSS.
